UNITED STATES PATENT OFFICE.

JAMES TYNER, OF NEW YORK, N. Y.

DESIGN FOR A BOTTLE.

60,591.

Specification for Design.

Patented Mar. 7, 1922.

Application filed January 20, 1920. Serial No. 352,880. Term of patent 3½ years.

To all whom it may concern:

Be it known that I, JAMES TYNER, a citizen of the United States, residing at New York, in the county of New York and State of New York, have invented a new, original, and ornamental Design for a Bottle, of which the following is a specification, reference being had to the accompanying drawing, forming part thereof.

Figure 1 is a plan view of a bottle; and

Fig. 2 is a cross-section of the same, showing my new design.

I claim:

The ornamental design for a bottle, as shown.

JAMES TYNER.
